UNITED STATES PATENT OFFICE.

JOHN E. BLAKE AND HENRY H. BLAKE, OF PITTSBURGH, PENNSYLVANIA, ASSIGNEES
TO BLAKE CRUSHER AND PULVERIZER COMPANY, OF PITTSBURGH, PENNSYLVANIA,
A CORPORATION OF PENNSYLVANIA.

FURNACE DEVICE.

1,009,217.

Specification of Letters Patent. Patented Nov. 21, 1911.

Application filed January 31, 1911. Serial No. 605,740.

To all whom it may concern:

Be it known that we, JOHN E. BLAKE and HENRY H. BLAKE, citizens of the United States, and residing in the city of Pittsburgh, in the county of Allegheny and State of Pennsylvania, have invented or discovered new and useful Improvements in Furnace Devices, of which the following is a specification.

10 Our invention consists in new and improved means for introducing a supply of heated air into a furnace or other combustion chamber to promote combustion of the fuel. The air is led downwardly through 15 a heated duct or passage in front of the furnace wall and introduced into the furnace at the bottom in a highly heated state. Controlling means are provided so that the supply of air may be cut off or regulated 20 at will.

We show novel means for providing access to the interior of the furnace with a slice bar or other tool, when necessary, and for closing the access orifice when not in 25 use to exclude the cold air and prevent escape of the heat. We show a novel closure for such orifice which consists of a door hinged to the front of the furnace and containing means for the downward introduction 30 of the air, preferably in the form of a combined duct and damper member.

Novel arrangements and construction of parts will appear from the following description.

35 In the accompanying drawings, which are however merely illustrative of a practical embodiment of the principles of our invention and not intended to limit the same to the construction shown, Figure 1 is a longitudinal, vertical section of a furnace fitted 40 with our invention taken along the line I—I in Fig. 2; Fig. 2 is a front elevation of a furnace fitted with three of our devices, the door of the left hand instalment being 45 shown open to disclose the orifice into the combustion chamber, the door in the central instalment being shown closed and the duct member raised, both door and duct being partially broken away, while the door in the 50 right hand instalment is shown closed and the duct member depressed, door and duct member being both partially broken away;

Fig. 3 is a horizontal section taken along the line III—III in Fig. 2; Fig. 4 is a perspective of the plate which we attach to the outside of the furnace wall; Fig. 5 is a similar view of the sliding duct member; Fig. 6 is a similar view of the door, while Fig. 7 is a plan view of the lever mechanism which controls the movement of the duct member.

55 The following is a detailed description of the drawings.

1 is the front wall of a furnace or combustion chamber, upon the outer face of which we bolt or otherwise secure a plate 2 provided with an inverted T shaped orifice or port 3 which is surrounded on all sides by a rearwardly extending flange 4 extending from the front to the rear face of wall 1 so that when the plate 2 is in place, the orifice 3, which extends into the interior of the combustion chamber is walled on all sides by the flange 4 and the brick work or other material of wall 1 is built up solidly against the flange 4 to support the plate. The orifice 3 is intended to permit the introduction of a slice bar or other tool into the furnace, when necessary, and the flange 4 protects the brick work of wall 1 from injury by the tool.

50 5 is a door member, hinged at one side to the plate 2 and provided with inwardly extending flanges at the sides and bottom, 6—6, which serve to space the front of the door away from the plate 2 and form therewith an open topped and closed bottom passage way for the descent of air.

55 7 is a port-closing and air-inlet controlling member, or duct member preferably formed as an elongated tube and provided with lateral flanges 8—8 which are mounted in slideways 9—9 on the inner face of door 5 to slidably support said duct on said door. The duct 7 is of sufficient width to close the vertical portion of orifice 3 and fits closely 60 up against the plate 2 when the door 5 is closed. The rear wall of duct 7 is extended laterally at the bottom to form damper plate 10 which, when the duct is depressed to its lowest position completely closes the lower portion of orifice 3 against the entrance of air into the combustion chamber. The duct 7 is raised or lowered by means of a connecting rod 11 pivoted to the duct and to

a hand lever 12 fulcrumed to the edge of door 5. A thumb nut and spring washer, 13, and 13^a, respectively, or some other convenient mechanism, is provided so that the lever 12 may be locked in any position to hold the duct 7 at any desired elevation.

The upper end of door 5 and of duct 7 may be left open for the natural entrance of air or may be connected with an air blast 10 device, not shown, for the introduction of air under pressure.

Means are provided, discharging into the top of the furnace, in front of the boiler, for supplying liquid or pulverized fuel to the 15 combustion-chamber; said means comprising pipes or tubes 14 (one thereof being shown in Fig. 1), which are fully shown and described in our previously-filed, copending application for patent for furnaces, Serial 20 No. 603,100, filed Jan. 17, 1911, and which form no part of the present invention.

The operation of our device is as follows. When access with a slice bar is desired, the door 5 is swung open and the orifice 3 is exposed, thus permitting of convenient manipulation of the bar. At other times the door 5 is kept closed against plate 2. If no air is to be admitted to the combustion chamber the duct 7 is depressed to its lowest 30 position, the damper 10 shutting the bottom of orifice 3 and preventing the entrance of air into the furnace. To admit air through the device, the duct 7 is raised and locked in its elevated position, whereupon air will 35 enter the top of the duct and the top of the door at either side of the duct and travel downwardly and enter the combustion chamber through the bottom of orifice 3. The air traveling down the duct 7 will become 40 highly heated owing to the fact that the rear wall of said duct is exposed to the furnace heat through the aperture 3, while the air traveling down the interior of the door at either side of the duct will also be heated. The amount of the air admitted 45 through the orifice 3 at the bottom will be regulated by the elevation of the duct 7 and its integral damper plate 10.

We preferably coat the rear face of door 50 5 and duct 7 with asbestos or some other non-conductor of heat to prevent the burning out of the members.

It is evident that our invention presents a 55 number of novel advantages, among which may be mentioned the thorough heating of the air before its introduction of the same into the combustion chamber, its introduction at the bottom where it is needed to promote combustion, and the ability of regulating 60 the quantity or cutting off entire the air admitted. Also the provision of convenient means for gaining access to the combustion chamber with a slice bar or other tool without injury to the furnace wall and 65 without requiring an open orifice which

would admit cold air into the combustion chamber or permit the escape of heat therefrom. Thus the furnace room is not unduly heated nor is there any loss of heat efficiency.

What we desire to claim is—

1. In furnace-construction, a plate securable to the exterior wall of a furnace combustion-chamber, and having a port adapted to communicate with the combustion-chamber, a door carried by said plate, and having a front wall, side walls, an open top and a closed bottom, and disposed in front of said port, and a port-closing and air-inlet controlling member reciprocable vertically between said door and said plate and spaced from said side walls of the door, leaving an air-passage on each side of said member between it and the adjacent side wall of said door, said member in its lowermost position entirely closing passage through said port. 85

2. In furnace-construction, a plate securable to the exterior wall of a furnace combustion-chamber, and having a port adapted to communicate with the combustion-chamber, a door carried by said plate, and having a front wall, side walls, an open top and a closed bottom, and disposed in front of said port, and a port-closing and air-inlet controlling member disposed between said door and said plate and slidably vertically in 90 bearings carried by said door, and spaced from said side walls of the door, leaving an air-passage on each side of said member between it and the adjacent side wall of said door, said member in its lowermost position 100 entirely closing passage through said port.

3. In furnace-construction, a plate securable to the exterior wall of a furnace combustion-chamber, and having a port adapted to communicate with the combustion-chamber, a door carried by said plate, and having a front wall, side walls, an open top and a closed bottom, and disposed in front of said port, a port-closing and air-inlet controlling member reciprocable vertically between said door and said plate and spaced from said side walls of the door, leaving an air-passage on each side of said member between it and the adjacent side wall of said door, said member in its lowermost position 115 entirely closing passage through said port, and manually-operable means connected with said member for controlling the movement thereof.

4. In furnace-construction, a plate securable to the exterior wall of a furnace combustion-chamber, and having an inverted, T-shaped port adapted to communicate with the combustion-chamber, a door carried by said plate, and having a front wall, side 120 walls, an open top and a closed bottom, and disposed in front of said port, and a port-closing and air-inlet controlling member reciprocable vertically between said door and said plate and spaced from said side walls of 125 130

the door, leaving an air-passage on each side of said member between it and the adjacent side wall of said door, said member in its lowermost position entirely closing passage 5 through said port.

5. In furnace-construction, a plate securable to the exterior wall of a furnace combustion-chamber, and having a port adapted to communicate with the combustion-chamber, said plate carrying a flange surrounding said port, a door carried by said plate, and having a front wall, side walls, an open top and a closed bottom, and disposed in front

of said port, and a port-closing and air-inlet controlling member reciprocable vertically 15 between said door and said plate and spaced from said side walls of the door, leaving an air-passage on each side of said member between it and the adjacent side wall of said door, said member in its lowermost position 20 entirely closing passage through said port.
